(57)

CLAIM

I claim the ornamental design for a grill grate cover, as shown and described.

DESCRIPTION

FIG. 1 is a front view of a grill grate cover, showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.
